(57) **CLAIM**

The ornamental design for a handle for medical device, as shown and described.

DESCRIPTION

FIG. 1 is a left side perspective view of a handle for medical device according to the present invention;

FIG. 2 is a right side perspective view of the handle for medical device of FIG. 1;

FIG. 3 is a front perspective view of the handle for medical device of FIG. 1;

FIG. 4 is a rear perspective view of the handle for medical device of FIG. 1;

FIG. 5 is a top perspective view of the handle for medical device of FIG. 1;

FIG. 6 is a bottom perspective view of the handle for medical device of FIG. 1; and,

FIG. 7 is a three quarter view of the handle for medical device of FIG. 1.

The dashed lines illustrate environment that does not form a part of the present invention, and no claim is made to the material illustrated with dashed lines.
